UNITED STATES PATENT OFFICE.

THEODORE LERCH AND HAROLD S. CLARK, OF CLEVELAND, OHIO.

CHEMICAL FIRE-ENGINE.

No. 880,676.

Specification of Letters Patent.

Patented March 3, 1908.

Application filed April 14, 1906. Serial No. 311,690.

To all whom it may concern:

Be it known that we, THEODORE LERCH and HAROLD S. CLARK, citizens of the United States, residing at Cleveland, in the county of 5 Cuyahoga and State of Ohio, have invented certain new and useful Improvements in Chemical Fire-Engines; and we do declare that the following is a full, clear, and exact description of the invention, which will enable others skilled in the art to which it 10 appertains to make and use the same.

Our invention relates to chemical fire engines, and the invention consists in the construction and combination of parts substantially as shown and described and particularly pointed out in the claims.

In the accompanying drawings Figure 1 is an elevation of the mixing tank or receptacle of the engine partly in section at the top and 20 showing the bottle suspended therein, and Fig. 2 is an elevation of the bottle and its supports partly in section, as hereinafter fully described.

The invention as thus shown is found, 25 first, in the means for carrying the main tank A, in which the chemicals are mixed as usual and which has the requisite opening for the emission of gas, not shown.

B is the supporting band for the tank 30 which is shrunk fixedly thereto, and b are trunnions secured to said band above the middle so as to throw the greater weight below the band and counterbalance the tank.

Another important feature of the invention is found in the means for closing and 35 opening and for supporting and tilting the lead bottle G contained in the outer receptacle or tank A. These means comprise several different elements, consisting of the 40 cover or cap H, constructed to seat in and upon the neck of the bottle substantially as shown and constituting a perfect stopper and seal therefor when down as in Fig. 2. Said cover H has a threaded stem h projecting

45 centrally through the top or head a on or for the outer or main tank, and said stem is provided with a crank wheel or handle h' to run the cap H quickly up on said stem off of neck g of inner bottle G when the engine is to 50 be used and the chemicals mixed. But a further operation occurs as the cap H is thus run up, which takes place in and through the arm 2 which is rotatably held on the neck of cap H at one end and extends downwardly to 55 about the middle of bottle G at one side thereof at its other end and at right angles to

the hangers J on which bottle G is supported at its bottom. Thus, the said bottle is shown as having an annular shoulder 3 near its bottom resting on and soldered to a band or ring L, and the hangers J pivotally engage this ring at g' off or at one side of the vertical center thereof, Fig. 2. Said hangers are rigid in or with tank top a, being threaded into the same in this instance, and 60 bottle G is adapted to rest and to be tilted between the same to discharge the contents, dotted lines Fig. 2. Arm 2 has an oblong slot 4 in its lower end adapted to engage a lug 5 on stem 6 rigid with ring L, and said 65 stem or standard 6 and arm 2 are on the short side of pivots or lugs g', so that when cap H is raised and bottle G would ordinarily tilt by gravity to position dotted lines Fig. 2, the 70 said bottle will be positively engaged by arm 2 and thrown to discharging position. This construction and arrangement of parts 75 also makes everything within and upon the main tank removable together, including top a which covers or incloses said tank, thus 80 working a great convenience for substituting a filled bottle.

To prevent creeping of gas out about threaded stem h we provide a seat a' on the under side of cap a adapted to engage a gasket 85 or packing h² about said stem and this may be further supplemented by packing about the base of said stem.

Another feature of convenience is the construction of hangers J which have open hooks 90 12 in which lugs or projections g' on ring L engage. The hangers J are rigid, and the hooks 12 are of substantially goose neck pattern with the point 13 of the hook extending back into the neck thereof across the 95 engaging point so that the bottle will be securely confined in said hooks for service while at the same time it can be easily removed and replaced.

What we claim is:—

1. In a chemical engine, a main tank and a support on which the tank is adapted to be tilted, a removable cover for said tank and hangers on the inside thereof, in combination with a bottle supported on said hangers in a 100 tilting position, and means to tilt said bottle comprising a screw engaged through said cover, a stopper for the bottle on said screw and an arm connected with said screw at one end and adapted to engage a stem on the 105 bottle support at its other end.

2. The main tank and the cover therefor

and rigid hangers from said cover having hooks at their lower ends bent inward over the engaging portion thereof, in combination with a bottle and a support therefor having 5 legs engaged in said hooks, an upright stem on said support, an arm engaging said stem and a screw through said cover on which said arm is supported, whereby when the said screw is run up the said arm is raised and 10 the bottle is tilted.

3. The main tank and the removable cover thereon, and a pair of hangers removably engaged in said cover, in combination with a bottle supported about its lower portion upon said hangers in a tilting position, a 15

device adapted to close the mouth of said bottle, a screw to raise said device and open the bottle and means connected with said device and bottle adapted to cause the said bottle to tilt, said means comprising a slotted 20 arm and a post from the bottle support engaged therein.

In testimony whereof we sign this specification in the presence of two witnesses.

THEODORE LERCH.
HAROLD S. CLARK.
